UNITED STATES PATENT OFFICE

JOHN L. MCATREE, OF BROOKLYN, NEW YORK, ASSIGNOR TO SCOVILL MANUFACTURING COMPANY, OF WATERBURY, CONNECTICUT, A CORPORATION OF CONNECTICUT

VANITY CASE

Original application filed March 17, 1928, Serial No. 262,533. Divided and this application filed December 2, 1930. Serial No. 499,452.

This invention relates to certain improvements in small boxes or cases for holding cosmetics commonly known as vanity cases, and is a division of my copending application Serial No. 262,533, filed March 17, 1928.

These cases are usually carried in a handbag, pocketbook, or a pocket of the user's apparel, and consequently should be as small and compact as practical. In addition, these cases should be of attractive appearance without protruding hinge or catch parts which mar the symmetry or contour of the boxes, and are liable to catch on other articles in the receptacles in which they are carried.

These boxes are made in two forms, a single case, that is, a case for holding one kind of toilet article as a compact, and a double case, that is, a case for holding two toilet articles as two compacts, and it is desirable that the case of either form be provided with a mirror.

It is the especial object of the present invention to provide a double box or case provided with an intermediate partition which may act as a mirror in which the parts are pivotally associated and in which a suitable catch is provided for holding the parts in closed relation, and in which the partition, the hinge and the catch are so arranged as to be entirely invisible when the box is closed, and a smooth box with no projecting parts is provided.

It is a further object of the invention to produce such a construction in which the catch may be fastened and released by a small rotary movement so that the box may be readily opened and closed.

With these and other objects not specifically referred to in view, the invention consists in certain novel parts, arrangements and combinations which will be described in connection with the accompanying drawings and the novel features pointed out in the claims hereunto appended.

In these drawings,—

Figure 1 is a top view of the improved box;

Figure 2 is a side view of the box shown in Figure 1;

Figure 3 is a central vertical section, on an enlarged scale, of the box shown in Figure

1, the section being taken on line 3—3 of that figure;

Figure 4 is a view, partly in section, showing the cover open and the mirror member seated in the cover;

Figure 5 is a sectional view showing the box in partly open position, and illustrating the manner of securing the central mirror in place;

Figure 6 is a sectional plan view, the view being taken on line 6—6 of Figure 3 showing the parts in unlocked position,

Figure 7 is a similar view showing the parts in locked position.

Referring now to these drawings, the box illustrated is a double box, that is, a box which will hold two compacts, and this double box will include a mirror, the parts being so arranged that the mirror is entirely within the box when the parts are closed and so associated that the body and the cover may be held in closed relation without any catch or hinge showing when so closed. In the particular construction illustrated, the box includes a body 1, a cover 2 and an intermediate partition 3, which preferably is in the form of a highly polished plate forming a mirror, with which the cover and the body are pivotally associated, as hereinafter more fully referred to. The box may be made of any suitable material, such as light metal, and preferably is circular and comparatively shallow, the cover and the body meeting in a thin edge so as to provide a small thin box of attractive appearance.

As illustrated, the body 1 is provided with side walls 4 which terminate in an inwardly and upwardly extending flange 5. The cover 2 is likewise provided with side walls 7 which terminate in a short inwardly extending flange 8, which, when the parts are closed as in Figure 2, seats on the inwardly extending portion of the flange 5 of the body 1.

In accordance with the invention, catch means for securing and releasing the body and the cover of the box are provided, and these means and the hinge before referred to will be so arranged that they are entirely invisible when the box is closed. Referring first to the catch devices, these will be of such

character that they may be operated from securing to release position by a relatively rotary movement of the parts. To effect this, in the box shown one of the members of the box carries catch devices which are arranged to engage with cooperating members on the other part of the box, these parts being arranged so as to be concealed when the box is closed, and the parts of the box are united so that they may have a relative rotary movement to secure and release the catch.

While the specific construction for effecting this may be varied within certain limits, in the particular construction illustrated the upwardly extending inset part 5' of the flange 5 is provided with nibs conveniently formed by punching out the wall of the flange, two of these nibs, marked 9, being shown, which are preferably arranged offcenter, that is, the nibs are not diametrically opposite each other.

The inturned flange 8 of the cover 2 is provided with two recesses, marked 10, which are similarly arranged as are the nibs 9, that is, preferably offcenter. The nibs are adapted to enter the recesses, as shown in Figure 6, whereupon, by a slight rotary movement of the cover and the body relatively to each other, the nibs 9 may pass under the flange 8 of the cover, as shown in Figure 7, and thus securely hold the body and the cover together. Of course, on the reverse movement of the parts the nibs are aligned with the recesses and the cover and the body may then be separated.

In accordance with the invention, means are provided for hinging the body and the cover together. Where, as in the present instance, an intermediate member, as the mirror 3, is employed, the body and the cover will be hinged to this intermediate member, the arrangement being such that the hinge and the member lie entirely within the box when the box is closed so as to be concealed, and, furthermore, means are also provided for permitting the relative movement of the body and cover above referred to. While the specific construction for effecting these functions may be somewhat varied, as shown, there is provided a bezel or annulus 11, of light metal, which is arranged to be secured in one of the members of the box, as, for instance, the cover. Where, as in the present instance, both the cover and the body are arranged to hold cosmetics, this annulus 11 may be formed with a downwardly extending central flange to form an aperture or well, indicated by dotted lines at 12 in Figure 4, and the well also being indicated in Figure 3. This annulus, in the particular construction illustrated, is held rigidly in place, the rotary movement between the body and the cover being provided for through means hereinafter referred to. While the annulus may be held in place in various ways, in the particular construction illustrated the annulus is formed with two

ears 13, which have comparatively thin edges so that they can engage under the flange 8 of the cover 2, before referred to.

In the particular construction illustrated, the mirror member 3 is pivotally associated both with the cover 2 and the body 1, so that these three parts are pivotally secured together and may be opened out so that the cosmetics in the cover and the bottom of the box are exposed and the mirror can be used at the same time. As illustrated in Figure 3, a part of the metal of the bezel or annulus is cut out or bent downwardly to form a leg 14, which in turn is cut out, as indicated at 15 in Figure 4, the metal at each end of the cutout being turned to form hinge knuckles 16. The metal of the partition is also provided with a cut out portion bent upon itself to form a knuckle 17, and a pintle pin 18 is passed through the knuckles 16, 17, hinging one edge of the mirror member 3 to the cover 2 of the box. Preferably the mirror member 3 is also cut away and bent on itself to form a knuckle 19 through which passes a pintle wire 20, which engages under the inwardly extending flange 5 of the box and is free to move around the flange so as to provide for the slight rotary movement of the parts, above referred to, for closing and opening the box.

In the best constructions, means are provided to limit the rotary movement and insure the nibs and recesses in the body and cover being in the correct position. While these means may vary in construction, the pintle wire 20, before referred to is provided with a loop 21, between the sides of which is located a pin 22 extending inwardly from the box body. This pin engaging the loop sides starts the rotary movement of the wire 20, the parts being arranged so that this movement is stopped at a point to insure the proper position of the nibs and recesses with respect to each other.

With this construction it will be observed that the partition member and the two hinges lie entirely within the walls of the cover and body members when the box is closed and are entirely concealed when the parts are in that position. Furthermore, the catch devices are also entirely concealed and can be operated by a very small relative turning movement of the parts to secure the parts together or to release them.

With the box described it will be observed that a very simple and compact case has been provided, one of attractive appearance and one in which the parts may be secured together and released in a very convenient manner.

While the invention has been shown and described in its preferred form, it will be understood that various changes may be made in the specific construction and arrangement of the details and parts described and

the invention is not to be limited to the exact form and construction of the parts disclosed.

What I claim is:

1. In a vanity case, the combination of a body and a cover, an intermediate metal mirror, hinge means concealed when the box is closed for connecting the body and cover to the partition at opposite edges thereof, so that the cover and body may fold over onto opposite sides of the partition and entirely enclose the same when the box is closed, and means for locking and releasing the body and cover by a relative rotary movement.
2. In a vanity case, the combination of a body capacitated to hold a compact, a cover capacitated to hold a compact, an intermediate partition having a mirror surface, a bezel in the cover having a compact holding well, means for securing the bezel in the cover, hinge knuckles carried by the bezel within the cover, a hinge knuckle on one side of the partition pivotally secured to the bezel knuckle, a hinge knuckle on the opposite side of the partition, a pintle wire in the body hingedly associated with the last named hinge knuckle on the partition and arranged to have a rotary movement in the body, the parts being arranged so that the partition and the knuckles are entirely concealed when the box is closed.
3. In a vanity box, the combination of a body and a cover each capacitated to hold a toilet article, an intermediate partition having a mirror surface, hinge means for connecting the intermediate partition to the body and the cover, cooperating locking devices on the body and the cover operable to locking and release positions by a relative rotary movement of the parts, said hinge means, partition and locking devices being entirely within the box when closed, and means for stopping the rotary movement of the parts to align the cooperating locking devices on the body and the cover.
- 45 In testimony whereof, I have hereunto set my hand.

JOHN L. McATREE.
